SOFA OR THE LIKE

Monte Le Roy Johnson, Culver City, Calif., assignor to

Capitol Chair Company, Inc., Culver City, Calif.

Application April 12, 1955, Serial No. 35,471

Term of patent 7 years

Fig. 1

I claim:

The ornamental design for a sofa or the like, substantially as shown.
